UNITED STATES PATENT OFFICE.

EUGEN URBAHN, OF BERLIN, GERMANY.

MEANS FOR SUPPORTING VACUUM-JACKETED BOTTLES OR OTHER RECEPTACLES
WITHIN INCLOSING CASINGS THEREFOR.

Application filed February 14, 1924. Serial No. 692,877.

To all whom it may concern:

Be it known that I, EUGEN URBAHN, a citizen of the German Republic, and a resident of Berlin, Germany, have invented certain new and useful Improvements in Means for Supporting Vacuum-Jacketed Bottles or Other Receptacles Within Inclosing Casings Therefor, of which the following is a specification.

10 This invention relates to means for supporting vacuum-jacketed bottles or other receptacles within inclosing casings therefor, and particularly to a device for resiliently supporting the bottle or receptacle 15 within the said casing and comprising a number of vertical spring-members or arms laterally engaging the outer wall of the bottle or receptacle and a resilient horizontally extending member engaging the lowermost 20 or bottom point of the said bottle or receptacle, all of the said members being united to form an exchangeable structure of interdependent resiliency.

It is known that vacuum-jacketed bottles 25 are very fragile and for this reason are usually enclosed in a metallic casing. The provision of the protecting casing, however, does not afford sufficient protection so that it has been found advisable to further protect the fragile glass body by means of resilient supports preferably provided in the bottom part of the casing so as to contact with both the casing and the bottle. The yielding supports hitherto suggested comprise coiled steel wires, flat steel springs 30 and the like; but the shape, construction and arrangement of the yielding members heretofore employed are such that a durable or lasting protection is not obtained 35 thereby mainly, since the yielding efficiency of said members soon decreases and the bottle then will be liable to fracture in case of any shock hitting the bottom of the bottle.

40 The object of this invention is to provide an improved support with a view to remedy this defect and which will form, as hereinbefore stated, a yielding bearing adapted to support the bottom part of the bottle 45 or receptacle both laterally and from below, the construction and arrangement of the parts being such that when a pressure or force is exerted upon or hits the encased bottle so as to be intercepted and counter- 50 acted by the resilient support, the laterally

engaging or contacting fingers or arms will tend, owing to the fact that all of the parts form a unit of interdependent resiliency, to converge with relation to each other or to a common central point lying within the longitudinal axis of the bottle, so that even if the resiliency or elasticity thereof diminishes in the course of time, still a reliable yielding support will be ensured for any 60 length of time.

65 In the accompanying drawing forming part of this specification an embodiment of the invention is shown by way of example, it being understood that changes in the form proportion, size and minor details may 70 be made within the scope of the claims without departing from the spirit or sacrificing any of the advantages of the invention. In the drawing Figure 1 is an elevation of a 75 jacketed bottle with the metallic casing broken away at the lower end thereof and Figure 2 is a perspective view showing the resilient support removed from the casing.

1 is the glass bottle of customary shape 80 and 2, 3 designate the bipartite metallic casing which is likewise of conventional construction. The bottom part 3 of the casing has a flat bottom 4 and is screwed into the main body 2 of the casing owing to the corrugated shape of the cylindrical side walls 85 of the two parts 2 and 3.

The resilient support 5 separately shown 90 in Figure 2 may be inserted into the bottom part 3 prior to the attachment of the latter to the main part 2 of the casing, as will be clearly understood from the drawing. The support 5 is made of flat steel strips, three strips 7, 8 and 9 of the particular shape shown in Figure 2 being employed to constitute the support, although 95 in some cases it may be advisable or desirable to employ more than three strips. The strips are assembled and connected together by means of a single rivet 6 so as to form a unit in the shape of what may 100 be called a tripod with the three feet 13 formed by a bend vertically elongated to at the same time form three upstanding resilient arms 10, 11 and 12, respectively, adapted to laterally engage or contact with 105 the outer wall of the glass bottle 1.

The distance of the free ends of the arms 10, 11 and 12 from each other or the radial distance thereof from the longitudinal axis of the glass bottle 1 is properly selected to 110

cause the arms, on assembling the parts, to yieldingly contact with the outer wall of the glass bottle without the necessity of overcoming any undue resistance opposed by the latter.

One of the three strips, in the embodiment shown the strip 7, is extended beyond the rivetting point and the elongated end 15 is bent and turned back to form a resilient seat 10 for the lowermost bottom point of the bottle. If a pressure is exerted on the turned-over end 15 of the strip 7 the end 15 will yield in the manner of a spring, but at the same time the parts of the three strips in the vicinity of the rivet 6 will likewise yield and move downwards and act as a spring or cushion in case that the three feet 13 are supported, say by the bottom 4 of the part 3 of the casing. By thus depressing the horizontal parts of the three strips the free ends of the upstanding arms 10, 11 and 12 will move radially inwards and exert a gripping action on any body, say the bottle 1, inserted therebetween, no matter whether they have been in a more or less slight touch with the latter previous to the depression of the horizontal parts of the strips, or not.

It will be seen that the bottle 1 duly supported in this manner, as shown in Figure 1, is protected from fracture in a by far better way than through the usual springs. Any shock or pressure accidentally imparted to the top or bottom of the vacuum-jacketed bottle will be yieldingly intercepted and counteracted by the resilient support 5, whereof the springy seat 15 acts like a buffer spring at the same time transmitting the received shock partly to the three lateral arms 10, 11 and 12 so that the effect of the shock will be distributed among and absorbed by the four yielding members 15, 10, 11 and 12 and no point of the glass bottle will be hit hard enough to undergo fracture through the action of the accidental shock.

The three arms keep the bottle always in centered position and obviously are adapted to individually absorb lateral shocks. The parts can be readily assembled by sliding the three arms of the support 5 onto and over the bottom of the glass bottle 1, inserting the thus combined two parts into the main body 2 of the casing and attaching the bottom part 3 of the casing to the main body by screwing the former into the latter, or dismounted by proceeding in the reverse order. It will be seen that the lowermost portion of the bottom part 3 of the metallic casing is circumferentially extended to form a circular groove 14 for the three feet 13 to engage therein either during or prior to the assemblage of the parts shown in Figure 1.

Although it has been found in practice that a support 5 comprising three resilient

strips answers well the object aimed at, it may be deemed convenient in some cases to provide more than three strips which would still come within the scope of the invention. For though I have described with great particularity of detail a specific embodiment of the invention, yet, as above intimated, such embodiment is only an example and it is not to be understood therefrom that the invention is limited to the particular embodiment disclosed.

What I claim is:

1. A device of the type described for resiliently supporting a vacuum-jacketed bottle or receptacle within an inclosing casing, comprising a number of radially arranged metallic strips firmly interconnected at their meeting point, feet (13) formed in said strips by bending, upstanding resilient arms (10, 11, 12) projecting from said feet, and a means over and above the said meeting point and spaced therefrom for yieldingly supporting the bottom of the bottle or receptacle, substantially as described.

2. A device of the type described for resiliently supporting a vacuum-jacketed bottle or receptacle within an inclosing casing, comprising a number of radially arranged resilient strips firmly interconnected at their meeting point, feet formed in said strips by bending, upstanding resilient arms projecting from said feet, and a yielding support (15) formed by the turned-over projecting inner end of one of the three strips and affording a seat for the bottom of the bottle or receptacle, substantially as described.

3. A device of the type described for resiliently supporting a vacuum-jacketed bottle or receptacle within an inclosing casing, comprising three radially arranged resilient strips firmly interconnected at their meeting point, a foot formed in each of the said strips, an upstanding resilient arm projecting from each foot, and a yielding support formed by the turned-over projecting inner end of one of the said three strips and affording a seat for the bottom of the bottle or receptacle, substantially as and for the purpose set forth.

4. In a device of the type described, the combination with a removable bottom section of a casing, of a resilient support for a vacuum-jacketed bottle or receptacle mounted in said bottom section, said support comprising a plurality of radially arranged metallic strips firmly interconnected at their meeting point, feet formed in said strips by bending, upstanding resilient arms projecting from said feet, and a means over and above the said meeting point and spaced therefrom for yieldingly supporting the bottom of the said bottle or receptacle, substantially as described.

In testimony whereof I affix my signature.
EUGEN URBAHN,
